UNITED STATES PATENT OFFICE.

ANNIS OLI RUSSELL, OF STORY CITY, IOWA.

RAILWAY SIGNAL.

Application filed September 11, 1922. Serial No. 587,476.

To all whom it may concern:

Be it known that I, ANNIS OLI RUSSELL, citizen of the United States, residing at Story City, in the county of Story and State 5 of Iowa, have invented certain new and useful Improvements in Railway Signals, of which the following is a specification.

The present invention relates to railway signals which are mechanically operated by 10 a train entering a section. The object of the invention is to provide signals of this character of simple construction and which are sure to function. For this purpose a signal post is erected in a suitable position near the 15 track and this signal post is adapted to be turned to show "danger" by the train entering from either end of the section, which signal will again be turned to "clear" directly the train has passed the post, mechan- 20 ical devices extending from the track connecting in both instances with the signal post to operate the same.

In the accompanying drawings one embodiment of the invention is illustrated and 25 Figs. 1^a and 1^b together form a plan view showing the general arrangement of the railway signal together with the railroad track from which it is operated;

Fig. 2 is a side elevation in larger scale of 30 the setting lever of the signal;

Fig. 3 is a front elevation of Fig. 2;

Fig. 4 is a side view from the right of Fig. 3;

Fig. 5 is a front view of a guiding block;

Fig. 6 is a vertical section along line 6—6 of Fig. 5;

Fig. 7 is a front elevation of the signal post;

Fig. 8 is a fragmentary vertical section 40 along line 8—8 of Fig. 14;

Fig. 9 is a side elevation of the releasing lever of the signal;

Fig. 10 is a vertical section along line 10—10 of Fig. 7;

Fig. 11 is a perspective view of a tensioning device for the cables;

Fig. 12 is a vertical section showing elastic connection between the different parts of the cable;

Fig. 13 is the stationary guide box for a cable connecting rod and

Fig. 14 is a horizontal section along line 14—14 of Fig. 7.

Referring particularly to Figs. 7, 8, 1^a

and 14 reference numeral 20 represents an 55 anchoring post set in the ground and having anchoring wings 19 and plates 21 extending sideways thereof to prevent the post from turning in the ground. This post is provided with a table shaped top 22 adapted 60 to form a turn table for the signal column 23, which is erected thereupon. The anchoring post 20 is further provided with a central pintle 24 extending upwardly from the turn table 22 and around which the signal 65 column 23 is adapted to turn.

The signal column 23 stands with its upper end sufficiently high above the ground to be visible at some distance with a signal board 25, upon which preferably a warning 70 such as "danger" or "stop" is shown. The signal column 23 has at its lower end an enlarged base 26 placed upon the turn table 22 of the anchoring post 20 and provided with a circumferential groove 27. At the lower 75 end of the base 26 is furnished rigidly connected to the latter an arcuate guide 28 intended to carry a coiled spring 29 abutting at one end against the base 26 as at 30 and at the other end against a loop 31 carried by 80 the turn table 22 in such a manner, that the coiled spring 29 tends to turn the base of the signal post 23 in the direction of arrow W Fig. 14. This turning is limited by means 85 of a nut or pin 32 engaging in the free end of the arcuate guide 28 on the opposite side to the spring 29 as regards the lug or loop 31.

Above the base 26 is provided a pair of collars 33 between which engage the fingers 90 of a clevis 34. This clevis has a socket 35 engaging the end of a shaft 36 extending from the signal column 23 over to the nearby track 37 where a bearing 38 is provided for the other end of the shaft 36 and is rigidly 95 secured upon a pair of ties 39. Extending to one side of the shaft 36 is a heavy weight 40 tending to turn the shaft in one direction to lift a lever 41 extending in opposite direction to the weight 40, the free end of the 100 lever 41 being wedge shaped as at 42 and positioned close to one of the rails of the track 37 in such a manner, that a wheel of a passing railway car will depress it, raising the weight 40 and slightly oscillating the shaft 36. The latter has adjacent to its end 105 engaging in the socket 35, a finger 43 intended to abut against a lug 44 provided on

the top of the base 26, in order to retain the signal column 23, when set in its "danger" position. When the wedge 42 of the lever 41 is depressed, it will then be evident that 5 the lifting of the finger 43 will disengage the lug 44 and permit the spring 29 to turn the signal column 23 into "clear" position.

Referring now particularly to Figs. 1^a, 2, 3 and 4, these figures represent the actuating or setting lever 50, normally upright which is rigidly attached to a shaft 49, revolvably mounted in a pair of bearings 51 and 52 secured on a tie 53 in any suitable manner as by means of bolts and the like. The 10 free end of the setting lever 50 carries a small roller 54, which is normally raised perpendicularly above the top face of a rail on the track 37 and adapted to be depressed by a wheel of a passing car. The roller 54 is held in a raised position by means of a counter-weight 55 rigidly carried at the opposite end of the shaft 49. Between the counter-weight 55 and the bearing 51 is loosely mounted upon the shaft 49 a sheave 25 56, to which is secured the end of a cable 58 by means of a transverse pin 57, in a suitable position in the groove of the sheave. The sheave carries a stud 59 normally contacting with the bearing 51, so that the 30 weight and tension of the cable 58 tends to hold the stud against the same, thereby preventing the sheave 56 from turning in opposite direction to arrow X, see Figs. 2 and 4. On the opposite side face of the 35 sheave 56 is provided another stud 60 positioned in such a manner that it will normally engage with an abutment 61 furnished on the counter-weight 55 as best seen in Fig. 4. It will now be seen that, from 40 the position of the rest of the different parts shown in full lines in Figs. 2, 3 and 4, a depression of roller 54 in the direction of arrow X, will cause the shaft with the counter-weight 55 to turn in the direction 45 of the arrow X and thus compel the sheave 56 to pull the cable 58 in the same direction through the intermediary of the abutment 61 and stud 60 and in this manner partly 50 wind the cable 58 upon the sheave 56, until the roller 54 has descended into the position indicated by dot and dash lines in Fig. 2.

In Figs. 5 and 6 is shown a guide box 62 carrying a pair of guide rollers 63 between which cable 58 is guided. This guide box 55 62 is preferably secured on top of the tie 64 by means of a screw 65 or the like.

In Fig. 11 is shown an adjusting device 55 for cable 58, the end of which is rigidly secured in a ring 66 at the opposite side 60 of which a rod 67 is attached by means of a nut 68 and locking key or pin. The rod 67, which is threaded and provided with transverse apertures for a cotter pin 71, engages the threaded end of the clevis 69. The 65 other end of the clevis engages the end of a

second cable 70 rigidly secured therein. It will now be evident, that by means of the threaded engagement between the adjusting rod 67 and clevis 69 the cables 58 and 70 may be tensioned to a suitable degree and held in such tension by means of the cotter pin 71. A guide box 62 of the same construction as already described is also furnished for cable 70 and secured to a tie 72, see Fig. 1^a. The other end of the cable 70 is secured to a tension rod 73 as at 74, see Fig. 12. This tension rod runs freely in a link 75 which is made in the shape of an elongated loop, to the opposite end of which a third cable 76 is rigidly secured as at 77. Upon the tension rod 73 is mounted a coiled compression spring 78 abutting against one end of the link 75 and engaging a washer 79 carried on the free end of the rod 73, the washer being held in position by a nut 80 threaded on the rod.

Referring to Figs. 1^a and 13 the end of cable 76 is secured to the looped end 85 of a sliding bar 89 carried in a guide box 90 provided with two pairs of guide rollers 91, between which the bar 89 is adapted to slide. This bar 89 extends through the box 90 to the other side thereof and terminates with a loop 94 of the same construction as the loop 85 engaging the cable 76 of the other end of the bar 89. To the loop 94 at this end is secured a fourth cable 95, while the loop is removably attached to the rod 89 Fig. 13.

The cable 95 is taken around a pulley or sheave 96 and is with its free end secured in the groove 27 of the base 26. This pulley 96 is revolvably mounted on the end of tension rod 97, carried in a guide box 98 of the same construction as guide box 90 already described, see Fig. 1^b. This guide box is also stationary and secured on a tie 99. The right end of the tension rod 97, as seen in Fig. 1^b, carries a loop 101 secured at one end of clevis 102 by means of a short cable 100. This clevis 102 is of the same construction as the clevis 69 already described. The adjusting rod 87 of this clevis engages a ring 103, to which is secured a fifth cable 104, which runs through a guide block 62 and is attached to one end of the elastic link 75, the tension rod 88 of which is fastened to a sixth cable 105 secured to a sheave 56 arranged and constructed in the same manner, as that already described in connection with the setting cable 58 at A on the left hand of Fig. 1^a. In other words the construction and operation of the parts 49, 50, 51, 52, 54, 55 and 56 are identical at both ends of the section. In order to distinguish between the actuating devices, the one to the left of Fig. 1^a will be denoted as actuating station A, the one at right hand end of Fig. 1^b as B and the releasing device near the signal column will be denoted as station C.

The operation of the railway signal is as follows:

Supposing that the signal is set for "clear," that is to say, the signal board 25 stands at right angles to the track, and that the actuating levers 50 at stations A and B as well as the actuating lever 41 at station C are all raised; a train approaching in right-hand direction as seen in Fig. 1^a will pass station A, when the wheels of the cars will contact with the roller 54 and depress lever 50 at this station. Cable 58 will then be wound up on the sheave 56 on account of the turning of shaft 49 in direction of the arrow X in Fig. 2 actuated by the contacting of abutment 61 with stud 60 in Fig. 4. As the pull on the cable 58 will be rather sharp, the elastic construction formed by the clevis 75 will come into play and prevent the breaking of the cables. This pull on the cable 58 will communicate through cables 76 and 95 to the revolving base 26 secured on the signal column 23 and turn the signal, so that the board will stand parallel with the track. It will be noted at this time that the pulley 96, around which the cable 95 is run, will remain stationary with the exception of a momentary deflection permitted by the elastic connection 75 at station B. The cable 105 attached to the sheave 56 at this station does not, however, move because the stud 59 of the sheave contacts against the side of the bearing 51 and prevents the rotation of the sheave in opposite direction to arrow X. The pull on the cable 95 compels the base 26 to turn in the direction of the arrow Y, Fig. 1^a, and set the signal to "danger," which turning amounts to about 90 degrees. Simultaneously the spring 29, see Figs. 7 and 14, will be compressed between abutments 30 and 31 upon its guide 28. As the base 26 of the signal column turns, the stop 44 on top thereof travels in the direction of arrow Y and passes under the finger 43 on the shaft 46, lifting the finger as it passes under. But directly the stop 44 is clear of the finger 43 the shaft 36 will be turned by its weight 40, so that the blunt end of the finger 43 stands in the path of the stop 44 and abuts against the same, thereby preventing the spring 29 from turning the signal to "clear."

As soon as the train has passed station A and approaches station C, the car wheels, encountering the wedge end 42 of the releasing lever 41 will depress this lever, thereby turning the shaft 36 and lift the finger 43 out of engagement with the stop 44, so that the spring 29 can then turn the signal to "clear." As the counter-weight 55 at station A, previous to the resetting of the signal, had been lifted, this weight will now have power to raise the actuating lever 50, and the spring 29 at station C will then pull the cables 58, 70 and 76 in the right-hand

direction of Fig. 1^a until they become taut assisted by the cable 95 and returned to the initial position shown in Fig. 1^a.

As soon as a train has passed station C and returned the signal to "open" and the lever 50 with the roller 54 into upright position ready for the next train, the first train when passing out over station B will then cause the roller 54 and the arm 50 at this station to swing outwardly, that is to say, in opposite direction to arrow X in Figs. 2 and 3. This will not effect the sheave 56 as the shaft turns freely therein. It will then be evident that the passing out of a train over station B will have no effect on the signal.

On the arrival of a train over station B, that is from the right hand side of Fig. 1^b, the passing car wheels will cause the swinging of the actuating lever in inward direction, that is, as indicated by arrow X in Figs. 2 and 4, producing the same effect on the signal as described in connection with a train arriving past station A. In this case a pulley 56 will then wind up a portion of cable 105 and pull on the cable 95, which, when passing over pulley 96, will cause the base 26 of the sign post 23 to turn as before and show "danger." The parts to the left of loop 94 on rod 89 and including cable 58 at station A, now remain stationary, with the exception of a momentary yielding in the elastic link 75. This yielding will, however, immediately cease and cable 76 return to its normal position. The resetting of the signal to open position will in this case be accomplished from station C by the actuating lever 41 in the same manner as already described.

Having thus described the invention, what is claimed as new is:

1. A railway signal system comprising a base, a signal post revolvably mounted on said base, means inserted between said base and said post tending to turn the post in one direction, an actuating lever adapted to be depressed by a passing car wheel over the railway track, and tensioning means between said actuating lever and said post; whereby, upon the depression of the actuating lever, the signal post will be turned through the intermediary of said tensioning means against the action of said turning means.

2. A railway signal system comprising a base, a signal post revolvably mounted on said base, means inserted between said base and said post tending to turn the post in one direction, an actuating lever adapted to be depressed by a passing car wheel over the railway track, and tensioning means between said actuating lever and said post; whereby, upon the depression of the actuating lever, the signal post will be turned through the intermediary of said tensioning means against the action of said turning means;

said turning means including a guide arm, a spring on said guide arm and an abutment on each of said posts and base, said spring having engagement with each of said abutments.

3. A railway signal system comprising a base, a signal post revolvably mounted on said base, means inserted between said base and said post tending to turn the post in one direction, an actuating lever adapted to be depressed by a passing car wheel over the railway track, and tensioning means between said actuating lever and said post; whereby, upon the depression of the actuating lever, the signal post will be turned through the intermediary of said tensioning means against the action of said turning means, said post having a stop, a finger mounted to oscillate in the path of said stop and to engage therewith after the turning of the post by said actuating lever and an element adapted to release the engagement between said finger and said stop.

4. A railway signal system comprising a base, a signal post revolvably mounted on said base, means inserted between said base and said post tending to turn the post in one direction, an actuating lever adapted to be depressed by a passing car wheel over the railway track and tensioning means between said actuating lever and said post; whereby, upon the depression of the actuating lever, the signal post will be turned through the intermediary of said tensioning means against the action of said turning means, said post having a stop, a finger mounted to oscillate in the path of said stop and to engage therewith after the turning of the post by said actuating lever and an element adapted to release engagement between said finger and said stop, said element including an arm rigidly connected with said finger, a weight on said arm adapted to hold the latter in raised position, said arm being situated adjacent to the railroad track and adapted to be depressed by the wheels of a passing train thereby lifting said finger.

5. A railway signal system comprising a base, a signal post revolvably mounted on said base, means inserted between said base and said post tending to turn the post in one direction, an actuating lever adapted to be depressed by a passing car wheel over the railway track and tensioning means between said actuating lever and said post; whereby, upon the depression of the actuating lever, the signal post will be turned through the intermediary of said tensioning means against the action of said turning means, bearings for said actuating lever, a counter-weight secured to the lever and tending to hold it in raised position, said tensioning

means including a cable, a sheave to which one end of the cable is attached, said sheave being revolvably mounted with relation to 65 said actuating lever, a stop for said sheave preventing the unwinding of the cable and inter-engaging elements between said weight and said sheave adapted to turn the sheave to wind up the cable.

6. A railway signal system comprising a base, a signal post revolvably mounted on said base, means inserted between said base and said post tending to turn the post in one direction, an actuating lever adapted to be 70 depressed by a passing car wheel over the railway track and tensioning means between said actuating lever and said post; whereby, upon the depression of the actuating lever, the signal post will be turned through the 75 intermediary of said tensioning means against the action of said turning means, bearings for said actuating lever, a counter-weight secured to the lever and tending to hold it in raised position; said tensioning 80 means including a cable, a sheave to which one end of the cable is attached, said sheave being revolvably mounted with relation to 85 said actuating lever, a stop for said sheave preventing the unwinding of the cable and inter-engaging elements between said weight and said sheave adapted to turn the sheave to wind up the cable, said tensioning 90 means further including an adjusting device and a yieldable clevis on the cable.

7. A railway signal system comprising a base, a signal post revolvably mounted on said base, means inserted between said base and said post tending to turn the post in one direction, an actuating lever adapted to be 95 depressed by a passing car wheel over the railway track and tensioning means between said actuating lever and said post; whereby, upon the depression of the actuating lever, the signal post will be turned through the 100 intermediary of said tensioning means against the action of said turning means, bearings for said actuating lever, a counter-weight secured to the lever and tending to hold it in raised position; said tensioning 105 means including a cable, a sheave to which one end of the cable is attached, said sheave being revolvably mounted with relation to 110 said actuating lever, a stop for said sheave preventing the unwinding of the cable and inter-engaging elements between said weight and said sheave adapted to turn the sheave to wind up the cable, said tensioning 115 means also including an adjusting device, a yieldable clevis on the cable and guide boxes with elastic connections with the cables.

In testimony whereof I affix my signature.

ANNIS OLI RUSSELL. [L. S.]
